LAWN TRIMMER BLADE FOR SPRINKLER HEADS

Floyd A. Terwilliger, 1232 SE. 12th Ave.,
Deerfield Beach, FL. 33441

Filed Sept. 22, 1966, Ser. No. 3,975

Term of patent 14 years

(Cl. D40—1)

FIG. 1

FIG. 3

FIG. 1 is a side elevation of a lawn trimmer blade for sprinkler heads, showing my new design;

FIG. 2 is an end elevation thereof; and

FIG. 3 is a plan view thereof, the opposite side being a mirror image of the side shown.

I claim:

The ornamental design for a lawn trimmer blade for sprinkler heads, as shown and described.
